(*) Notice: This patent is subject to a terminal disclaimer.

(57) **CLAIM**

(**) Term: **14 Years**

The ornamental design for a two handle faucet, as shown and described.

(21) Appl. No.: **29/151,968**

DESCRIPTION

(22) Filed: **Dec. 13, 2001**

FIG. 1 is a front perspective view of the two handle faucet showing our new design;

(51) LOC (7) Cl. **23-01**

FIG. 2 is a rear perspective view thereof;

(52) U.S. Cl. **D23/242; D23/241**

FIG. 3 is a top plan view thereof;

(58) Field of Search **D23/223, 238-243,**

FIG. 4 is a right side elevational view thereof;

D23/250-257; 4/675-678; 137/801

FIG. 5 is a front elevational view thereof;

D377,516 S * 1/1997 Doughty et al. D23/241

FIG. 6 is a rear elevational view thereof;

D293,362 S * 12/1987 Hill et al. D23/241

FIG. 7 is a left side elevational view thereof; and,

D318,717 S * 7/1991 Spangler D23/252

FIG. 8 is a bottom plan view thereof.

D321,750 S * 11/1991 Spangler D23/241

The broken line showing of the handles, lift rod and spout tip in FIG. 1 are for purposes of illustration only and form no part of the claimed design.
